UNITED STATES PATENT OFFICE.

WILLIAM KILMER, SR., OF BROOKLYN, IOWA.

PROPORTIONATE FEEDING DEVICE FOR CONCRETE-MIXERS.

1,247,409.

Specification of Letters Patent. Patented Nov. 20, 1917.

Application filed September 11, 1916. Serial No. 119,453.

To all whom it may concern:

Be it known that I, WILLIAM KILMER, Sr., a citizen of the United States, and resident of Brooklyn, in the county of Poweshiek and State of Iowa, have invented a certain new and useful Proportionate Feeding Device for Concrete-Mixers, of which the following is a specification.

The object is to provide a proportionate feeding device for a concrete mixer so constructed and arranged that the relative proportion of cement and sand may be varied according to the wish of the operator.

A further object is to provide such a machine in which the cement and sand are fed to a mixing cylinder or chamber in such a way as to facilitate a thorough admixture of the ingredients in the mixing chamber.

Still a further object of my invention is to provide such a machine adapted to allow the ingredients to fall from the bottom of the hopper directly into the mixing chamber, whereby a tendency of the parts to become stalled on account of obstruction is lessened.

Still a further object of my invention is to provide a combined closure device and agitating device constructed in such a manner that the amount of each ingredient fed from the hopper may be regulated by adjusting said device.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of a machine embodying my invention.

Fig. 2 shows a horizontal, sectional view of the same, taken on the line 2—2 of Fig. 3.

Fig. 3 shows a vertical, longitudinal sectional view through the machine.

Fig. 4 shows a vertical, transverse sectional view, taken on the line 4—4 of Fig. 3, and

Fig. 5 shows a perspective view of one of the sliding members whereby the flow of the ingredients is controlled.

In the accompanying drawings I have used the reference numeral 10 to indicate generally the frame of my concrete mixing machine, which is mounted upon suitable supporting wheels 11. A tongue 12 may, if desired, be connected with the frame for the

purpose of drawing the machine from place to place.

Suitably mounted on the frame, preferably near one end thereof, is a transverse shaft 13, which as shown in the drawings is located near the front of the machine. On one end of the shaft 13 is a suitable means such as the pulley wheel 14, for connecting the shaft 13 with the source of power.

Mounted on the frame preferably rearwardly of the shaft 13, is a mixing cylinder or receptacle 15, the upper portion of which is open, as shown in Fig. 3. At the rear end of the cylinder 15 is a discharge tube 16 communicating with the bottom of the cylinder. Mounted in the front and rear walls of the cylinder is a shaft 17 on the forward end of which outside the mixing receptacle 15 or cylinder is a bevel gear 18 in mesh with the bevel gear 19 on a counter shaft 20. On the shafts 13 and 20 are pulleys 21 and 22, on which travel the belts 23 for transferring power from the shaft 13 to the shaft 17. On the shaft 17 is a screw 24, and on the blade of the screw is a plurality of flanges 25 which facilitate thorough mixing of the contents of the receptacle 15. On the shaft 17 near each end of the receptacle 15 is a bell-shaped shield 26 to protect the bearings of the shaft 17 from the sand and cement.

Mounted above the rear end of the receptacle 15 is a water tank 27 having at its lower forward portion a discharge cock 28 adapted to discharge into the mixing cylinder or receptacle at a point spaced from the rear end thereof.

Above the forward portion of the mixing receptacle is a hopper 29 supported by members 30 on the frame 10. In the hopper 29 is a transverse partition 31. Slidably mounted on the frame below the hopper 29 are bars 32 on opposite sides of the receptacle 15, which bars are connected at their forward ends by a member 33. A bar 34 extends forwardly in the machine from the member 33 between guide rollers 35. The bars 32 travel between the rollers 36 mounted on the upright supporting members 30.

Mounted between the bars 32 and the frame 10 are transverse adjustable closure devices, each comprising an upper flat bar 37, having a plurality of spaced upwardly extending pins or the like 38. Below each bar 37 is a pair of parallel horizontal bars 39.

Below each pair of bars 39 is a transverse bar 40. The bars 40 and 37 are secured to the bars 32 by means of bolts 41 on which are nuts 42. By screwing the nuts 42 tightly on the bolts 41 the bars 39 are gripped between the bars 40 and the bars 37. By loosening such nuts the bars 39 may be spread apart or moved together for varying the total width of the closure devices. The bottom of the hopper 29 is contracted somewhat, as shown in Fig. 3, and is open. The closure devices are so arranged with relation to each other that they stand below the respective compartments formed on each side of the partition 31.

Pivoted to the bar 34 is a pitman 43 which extends forwardly and downwardly and is operatively connected at its forward end to a crank 44 on the shaft 13. The lower rear wall of the hopper 29 is hinged at 45 and the lower end of the partition 31 is hinged at 46. Pivoted to the lower hinged member 46^a of the partition 31 is a rod 47 extending rearwardly in the machine through an opening 48 in the lower hinged hopper member 49. On the rod 47 outside the hopper is a coil spring 50 and on the outer rear end of the rod 47 is an adjustable thumb nut 51, whereby the tension on the spring 50 may be varied. Extending from the partition 31 above the line of the hinges 46, downwardly and forwardly, is a partition 52 lying spaced beneath it for the operation of the hinged member 46^a.

In the practical operation of my improved concrete mixing machine, the machine is set in operation by means of any suitable source of power. It will be seen that the screw 24 will be rotated through the mechanism hereinbefore described, and that the bars 32 will be reciprocated carrying with them the closure devices above described. The concrete and sand are simultaneously poured into the compartments of the hopper. The cock 28 may be turned for allowing any desired flow of water from the tank 27. The cement and sand will flow downwardly past the closure devices as the closure devices are reciprocated. On account of the fact that when the closure devices are at any except their central positions, that part of the lower ends of the compartments of the hopper will be open. The closure devices may be reciprocated with such rapidity that the sand and cement is fed downwardly and is then thrown rearwardly and forwardly by the closure devices so as to scatter such ingredients and thus facilitate their thorough admixture. The mixing is completed by means of the screw 24 and flanges 25, so that by the time the mixture reaches the discharge tube 16 the mixing is completed.

By varying the positions of the bars 39 and of the two closure devices, the relative rate of feed of the sand and concrete may

be varied so that the relative proportions of such ingredients in the completed mixture may be regulated as desired.

Attention is called to the hinged members 46 and 49 and the spring device for holding them in proper position. On account of the construction herein described, of said hinged members, if a rock or large pebble should be fed downwardly it can pass between the pins 38 and the member 46 or the member 75 49, as the case may be, without injury to the machinery.

It will thus be seen that with my improved concrete mixer concrete may be mixed with any desirable relative proportions of cement and sand, and that the entire mixing process is performed by the machinery. The amount of water supplied to the mixture may be varied by means of the cock 28.

My device is mounted on wheels so that it may be readily portable. It will be seen from the foregoing description that the machinery of my mixer is comparatively simple and that the entire machine may be made at a comparatively small expense, so that the machine may be used on small jobs. An engine or other suitable source of power may, if desired, be mounted upon the frame 10.

It will be understood that some changes may be made in the arrangement and construction of the parts of my concrete mixer, without departing from the essential features and purposes of my invention, and it is my intention to cover by my present application any such changed forms of construction which may be included within the reasonable scope of my claims.

I claim as my invention:

1. In a device of the class described, a frame, a pair of hoppers mounted on said frame adjacent to each other and having discharge openings in the bottom thereof, a second frame adapted to reciprocate on the first frame beneath the discharge openings of said hoppers, a pair of spaced transverse bars fixed to said second frame and adapted to rest beneath the discharge opening of each hopper when the frame is in an intermediate position relative to the limits of its reciprocation, a pair of spaced bars adapted to be received between the parts of the first described pair of bars and to extend therefrom toward the ends of the second described frame, and means for securing said last described bars in any desired position relative to the distance which they extend from said first described pairs of bars.

2. In a device of the class described, a frame, a pair of hoppers mounted on said frame adjacent to each other and having discharge openings in the bottom thereof, a second frame adapted to reciprocate on the first frame beneath the discharge openings

of said hoppers, a pair of spaced transverse bars fixed to said second frame and adapted to rest beneath the discharge opening of each hopper when the frame is in an intermediate position relative to the limits of its reciprocation, a pair of spaced bars adapted to be received between the parts of the first described pair of bars and to extend therefrom toward the ends of the second described frame, and agitating members fixed to the upper bar of each of said first described pairs of bars and extended upwardly therefrom.

5. In a device of the class described, a hopper having an elongated discharge opening near the bottom thereof, a frame member adapted to reciprocate beneath said dis-

charge opening, the direction of the motion of said frame being perpendicular to a line through the long way of said discharge 20 opening, a pair of spaced transverse bars fixed to said frame, a second pair of bars secured between the first pair of bars and adapted to have one side edge extend beyond the opposite side edges of the first described 25 bars, means for varying the distance, which the edges of said second pair of bars extend beyond the edges of said first pair of bars, and means for reciprocating said frame.

Brooklyn, Iowa, Sept. 1st, 1916.
